UNITED STATES PATENT OFFICE

CHARLES EMIL CHRISTIAN RADEMACHER, OF ST. ALBANS, NEW YORK

SUBMARINE ESCAPE

Application filed August 4, 1931. Serial No. 555,082.

An object of the invention is to provide an escape for submarines having a chamber with an entrance and an exit, with means within the chamber for closing the entrance 5 to and the exit from the chamber.

Another object of the invention is to provide a chamber with a plunger for forcing water from the chamber after the entrance has been closed and the exit has been opened 10 to permit of the closing of the exit and the withdrawal of the plunger from the exit with the chamber free from water.

Other objects of the invention are to provide means for opening and closing a head at 15 the exit of the chamber, the said means being operable from within as well as from without the chamber, and to provide means operable from within as well as from without the chamber to secure the door at the inlet. The plunger is preferably provided 20 with a check valve or valves and means are provided for moving the plunger in the cylinder. Means are also provided for locking the head at the exit from the chamber.

Additional objects of the invention will appear in the following specification in which the preferred form of the invention is described.

In the drawing similar reference characters 25 refer to similar parts in the several views, of which

Figure 1 is a sectional view showing the escape device in connection with a submarine, a portion of which is shown in section,

Figure 2 is a sectional view similar to the 30 sectional view illustrated in Figure 1, but with the head at the exit from the chamber in open position, and

Figure 3 is a sectional view on the line 3—3 35 of Figure 1.

By referring to the drawing it will be seen that the escape device is arranged on a submarine, a portion of which is shown in section at 5, the device including a chamber 6 which is preferably in the form of a cylinder 40 and which has an exit opening 7 at one of its ends and an inlet opening 8, which is preferably at the top of the chamber or cylinder 6. The opening 7 is closed by a head 9 which is pivoted at 10, the head 9 having a gasket 11

for engaging the end of the cylinder to obtain a tight joint. Secured to the head 9 there is an arm 12 which has a pin and slot connection 13 with a rod 14, the rod 14 extending through an opening 15 in the submarine, 55 which is provided with a stuffing box 16 to prevent leakage, the rod 14 being journaled in a bearing 17 in a depending gear box 18. The rod 14 is threaded, as shown at 19, and meshing with this thread there is a nut 20 having outer teeth 21 and an integral sprocket wheel 22. A sprocket chain 23 is disposed around the sprocket wheel 22, by which means the nut 20 may be rotated and, as this nut 20 and sprocket wheel 22 are rotated between a 60 bearing 24 and the wall 25 of the gear box 18, the rotation of the nut serves to move the rod inwardly or outwardly, as may be desired, to open or close the head 9. The chamber or cylinder 6 has a depression 26 with a 70 bearing 27 and journaled in this bearing 27 there is a stub shaft 28 on which there is mounted a gear 29 which meshes with the teeth 21 of the nut 20. At the inner side of the stub shaft 28 there is a handwheel 30 and 75 it will, therefore, be understood that by turning the handwheel 30 within the interior of the chamber or cylinder 6, it is possible to open or shut the head 9 as may be desired. Therefore, this head 9 may be opened or may 80 be shut, either from within or from without the chamber or cylinder 6.

The inlet 8 has an outwardly extending rim 31 and a bracket 32, a door 33 being hinged to the bracket 32, this door 33 being preferably provided with a handle 34, by which means the door 33 may be conveniently opened or closed from within the chamber or cylinder 6. The door 33 has also an extending arm 35 which is positioned for engagement by a locking member 36, this locking member 36 being pivoted to a bracket 37 at the outer side of a hood 38 extending from the chamber or cylinder 6. This hood 38 has an opening 39 through which is disposed an arm 40 on the 95 locking member 36, the locking member 36 also has an outwardly extending arm 41, so that the locking member 36 may be operated either from within or from without the chamber or cylinder 6. The locking member 36 is 100

provided with an opening 42, so that when the locking member 36 is positioned as illustrated by the full lines in Figure 1 of the drawing, the arm 35 on the door 33 will be disposed in the said opening 42 and will be held secured by engagement with a surface of the locking member 36. However, when the locking member 36 is moved to the position indicated by the dotted lines in Figure 1 of the drawing, the arm 35 will be free from the locking member 36, so that the door 33 may be opened, as illustrated in the dotted lines in Figure 1. Secured to the arm 40 at the inner side of the hood 38, there is a gasket or washer 42' which serves to prevent the escape of water from the chamber or cylinder 6 through the opening 39.

Disposed in the chamber or cylinder 6 there is a plunger or piston 43, the plunger or piston 43 having valve openings 44 which are normally closed by flaps or other check valves 45, which prevents fluid from passing from the chamber or cylinder 6 at the opening 7 through the valve openings 44, while permitting air to flow from the head 46 of the cylinder through the valve openings 44 into the cylinder adjacent its head 9. There are openings 47 in the head 46 which permit a flow of air through the head 45 to and through the valve openings 44.

The head 46 is provided with a bearing 48 and a bracket 49 is secured to the head 46, a screw 50 being provided which is journaled in the bearing 48, this screw 50 also being journaled in a bearing 51 in the plunger or piston 43. Meshing with the screw 50 there is a nut 52 having sprocket teeth 53 around which a sprocket chain 54 is disposed. It will be understood that the longitudinal movement of the nut 52 is prevented by the bearing 48 and the bracket 49, and that, therefore, when the nut 52 is rotated by the sprocket chain 54 and sprocket teeth 53, it will serve to move the screw 50, together with the plunger or piston 53, longitudinally of the chamber or cylinder 6.

The head 9 is provided with a threaded projection 55 which is disposed for disposal in a threaded opening 56 in a member 57 which has longitudinal and rotary movement in a bearing 58 in the submarine 5. The member 57 is provided with a handwheel 59, so that when the threaded projection 55 is disposed at the threaded opening 56 in the member 57, the handwheel 59 may be rotated to lock the threaded projection 55 in the member 57. A resilient packing 60 is disposed in the bearing 58 to permit the longitudinal and rotary movement of the member 57, as may be necessary, to secure and lock the threaded projection 55 on the head 9, while preventing water from passing through the bearing 58.

It will be understood that the device which has been described may be disposed at any desired place on the submarine and that with

the head 9 in closed position and the plunger or piston 43 disposed adjacent the head 46, the door 33 may be opened, when a man may enter the chamber or cylinder 6, after which the door 33 may be closed, and should there be only one man remaining in the submarine, this door may be secured from the interior of the chamber by means of the arm 40, but where there are other men remaining in the submarine, the door may be secured, if desired, by means of the arm 41. When the door 33 has been closed and has been secured, the member 57 may be turned to free the threaded projection 55, when the head 9 may be turned slowly, either from within or from without the chamber or cylinder 6, when the water will flow into the chamber or cylinder 6, and when the chamber or cylinder 6 has been filled with water, the man within the chamber may leave through the exit 7, the man being provided with a suitable means to withstand water pressure and to supply him temporarily with air. When the man has escaped, the plunger or piston 43 may be moved in the direction of the head 7 to expel water from the chamber or cylinder 6, after which the head 9 may be closed by the means which has been described and after which the piston 43 will be moved again to a position adjacent the head 46, the check valves 45 permitting air to enter the chamber or cylinder 6, when the door 33 may be opened again to permit another man to enter the chamber or cylinder and make his escape in the manner described. It will be understood that when the member 57 has been moved to free the threaded projection 55, it will not be necessary to operate this member 57 to lock the door during the period between the escape of two sailors, inasmuch as the head 9 will be held in position at the exit 7 by the water pressure. Therefore, when one or more sailors are about to escape from the submarine, the member 57 will be moved to free the threaded projection 55 and this projection 55 will not be locked again during the escape of the crew from the submarine.

What is claimed is:

1. In a submarine escape, a chamber having an exit, a head for closing the exit, a plunger in the chamber and fitting the chamber snugly for moving in the direction of the exit to eject water from the chamber through the exit, the chamber having an entrance, a door for closing the entrance, and a check valve or valves in the plunger.
2. In a submarine escape, a chamber having an exit, a head for closing the exit, a plunger in the chamber and fitting the chamber snugly for moving in the direction of the exit to eject water from the chamber through the exit, a threaded spindle secured to the plunger, a nut meshing with the thread on the spindle, means to limit the movement of the nut longitudinally of the spindle, means

to rotate the nut, the chamber having an entrance, and a door for closing the entrance.

3. In a submarine escape, a chamber having an exit, a head for closing the exit, a plunger in the chamber and fitting the chamber snugly for moving in the direction of the exit to eject water from the chamber through the exit, a threaded spindle secured to the plunger, a nut meshing with the thread on the spindle, means to limit the movement of the nut longitudinally of the spindle, means to rotate the nut, the chamber having an entrance, a door for closing the entrance, and a check valve for the plunger.

13 4. In a submarine escape, a chamber having an opening, a pivoted head for closing the opening, an arm secured to the pivoted head, a threaded rod, means connecting the threaded rod with the arm for moving the head relatively to the chamber, a bearing in a wall of the chamber, a stub shaft journaled in the bearing, a handwheel on the stub shaft and disposed within the chamber, a nut meshing with the thread on the rod, and gearing connecting the stub shaft with the nut.

5. In a submarine escape, a chamber having an opening, a head for closing the opening, there being another opening in a wall of the chamber, a door for closing the second mentioned opening, an arm on the door, there being a third opening in a wall of the chamber, a locking member pivoted at the third mentioned opening, the locking member having means for securing the arm, an operating arm on the locking means extending through the third mentioned opening into the chamber, and means on the operating arm for closing the third mentioned opening.

6. In a submarine escape, a chamber having an opening, a pivoted head for closing the opening, an arm secured to the pivoted head, a threaded rod, means connecting the threaded rod with the arm for moving the head relatively to the chamber, a bearing in a wall of the chamber, a stub shaft journaled in the bearing, a handwheel on the stub shaft and disposed within the chamber, a nut meshing with the thread on the rod, gearing connecting the stub shaft with the nut, there being another opening in a wall of the chamber, a door for closing the second mentioned opening, an arm on the door, there being a third opening in a wall of the chamber, a locking member pivoted at the third mentioned opening, the locking member having means for securing the arm, an operating arm on the locking member extending through the third mentioned opening into the chamber, and means on the operating arm for closing the third mentioned opening.

7. In a submarine escape, a chamber having an opening, a pivoted head for closing the opening, an arm secured to the pivoted head, a threaded rod, means connecting the threaded rod with the arm for moving the

head relatively to the chamber, a bearing in a wall of the chamber, a stub shaft journaled in the bearing, a handwheel on the stub shaft and disposed within the chamber, a nut meshing with the thread on the rod, gearing connecting the stub shaft with the nut, there being another opening in a wall of the chamber, a door for closing the second mentioned opening, an arm on the door, there being a third opening in a wall of the chamber, a locking member pivoted at the third mentioned opening, the locking member having means for securing the arm, an operating arm on the locking member extending through the third mentioned opening into the chamber, means on the operating arm for closing the third mentioned opening, the head having a threaded projection, a bearing, and a member movable in the bearing and having a threaded opening in which the threaded projection meshes.

8. In a submarine escape, a chamber having an exit, an inlet, an outwardly disposed hood and a depression, a head for closing the exit, a plunger in the chamber fitting the chamber snugly for moving in the direction of the exit to eject water from the chamber through the exit, a door for closing the inlet, a check valve in the plunger, means for securing the door operable in the hood, and means operable from the depression for moving the head relatively to the chamber.

9. In a submarine escape, a chamber having an exit, an inlet and a depression, a head for closing the exit, a plunger in the chamber and fitting the chamber snugly for moving in the direction of the exit to eject water from the chamber through the exit, a door for closing the inlet, a check valve in the plunger, and means operable in the depression for moving the head relatively to the chamber.

10. In a submarine escape, a chamber having an exit, an inlet and an outwardly disposed hood, a head for closing the exit, a plunger in the chamber fitting the chamber snugly for moving in the direction of the exit to eject water from the chamber through the exit, a door for closing the inlet, a check valve in the plunger, and means for securing the door operable in the hood.

11. In a submarine escape, a chamber having an opening and a depression, a plunger for moving in the chamber, a pivoted head for closing the opening, an arm secured to the pivoted head, a rod, means connecting the rod with the arm for moving the head relatively to the chamber, and means within the depression for operating the rod from within the chamber.

CHARLES EMIL CHRISTIAN RADEMACHER. 125
